ATTORNEY

UNITED STATES PATENT OFFICE.

ALEXANDER P. WHITE, OF NEW YORK, N. Y., ASSIGNOR TO THE AMERICAN METAL LATH COMPANY, OF NEW JERSEY.

EXPANDED METAL STRUCTURE.

SPECIFICATION forming part of Letters Patent No. 651,642, dated June 12, 1900.

Application filed December 12, 1898. Renewed March 29, 1900. Serial No. 10,699. (No model.)

To all whom it may concern:

Be it known that I, ALEXANDER P. WHITE, of the city and State of New York, have invented certain new and useful Improvements 5 in Expanded Metal Structures, of which the following is a description, referring to the accompanying drawings, which form a part of this specification.

The object of the invention is to improve 10 expanded metal structures—such as are used, for example, for metal lathing—so that the plaster may be held in a more secure and efficient manner and at the same time that the thickness of the plaster or mortar may be reduced.

The invention relates to the class of structures in which a series of slots are cut parallel with each other and of equal length, and the structure is then expanded so that the 20 strips of metal between the cuts form a parallel slotted construction.

In order to render a prolonged description of the general art to which my invention relates unnecessary, I refer to the patent to 25 Gibson, No. 451,418, granted April 28, 1891, and the patent to Hilton, No. 588,576, granted August 24, 1897.

In all prior constructions of this nature with which I am acquainted the slats or strips 30 of the metal when expanded lie more or less directly edgewise to the original plane of the sheet. I have discovered that it is possible to roll, fold, or otherwise turn the slats so that they all lie in the same plane, thereby 35 not only decreasing the necessary thickness of the plaster coating which is to be applied to them, but also greatly decreasing the space between neighboring slats or strips, while increasing the grip or hold which the slatted 40 structure will have upon the plaster. In short, the approaching edges of neighboring slats come nearer together and at the same time form opposing sharp edges lying in the same plane for holding the plaster.

45 The accompanying drawings illustrate the preferred form of my invention as applied to an expanded metal structure.

Figure 1 shows a portion of such a struc-

ture embodying my invention. Fig. 2 is a plan view of Fig. 1; Fig. 3, a section on the 50 plane of 33 of Fig. 1, and Fig. 4 a modification.

Throughout the drawings like letters of reference indicate like parts.

In Figs. 1, 2, and 3 the slats S are flattened 55 or turned into a common plane, as is clearly seen in Figs. 2 and 3; but each slat has been turned on its longitudinal axis one hundred and eighty degrees, so that its rear face is turned to the front and its front face turned 60 to the rear of the structure. Fig. 4 differs from this form only in having the slats S flattened or turned, just as though they had never been displaced from the original plane, though, of course, the ends of all the slats are bent, 65 folded, or corrugated by the deforming or expanding of the original sheet to form the open-work slatted structure.

I have purposely omitted any illustration of the general arrangement of the sheet as a 70 whole, its continuation toward the right being indicated in dotted lines, Fig. 2, since the channels which it is customary to form between the several series of slats may be of any shape without interfering with my invention, which relates only to the flattening 75 of the slats into a common plane or substantially to a common plane. Obviously if the slats are only partly flattened the purposes of my invention will be fulfilled to a lesser 80 degree than if they are actually flattened out, as illustrated. In practice I prefer to perfect the flattening by means of machinery, either pressing the slatted structure under a suitable pressure after it has been expanded 85 or by rolling the slats, so as to flatten them under the action of a roller the face of which is somewhat shorter than the length of each slat. The manner of constructing my improved form of structure is, however, immaterial 90 to my invention.

I claim, and desire to secure as the novel and characteristic features of my invention, the following:

1. The expanded metal structure of sheet 95 metal, comprising one or more parallel series

of slats or laths, separated by intervals and flattened so as to lie substantially in the same common plane, substantially as set forth.

2. The expanded metal structure of sheet metal formed of slotted sheet metal stretched into a plaster or mortar holding open-work, the slats or strips of which are turned or flattened toward their common plane, thereby

narrowing the intervals between neighboring slats, substantially as set forth. 15

Signed this 7th day of December, 1898, at New York, N. Y.

ALEXANDER P. WHITE.
